CHANNEL-TYPE WEATHER STRIP

Elmer D. Barringer, Cleveland, Ohio

Application July 15, 1935, Serial No. 31,497

7 Claims. (Cl. 20—69)

In the art of weatherstrip installation today, there is commonly used in conjunction with so-called French windows, or windows in which the swinging casement type of sash are employed, what are known as channel weatherstrip members or devices that are located upon the sill of the window frame below the swinging sash.

These channel weatherstrip devices, called channels, are designed to receive and carry off water which may leak past the weatherstrip means intermediate the sash and the channel, so as to prevent the water or moisture from reaching the inside of the window or sash.

In order to prevent water thus received and passing off from the channel from contacting with the wood of the sill portion of the frame, which in time would cause a rotting away of this wood, it has been proposed heretofore to dispose below said channel, and on the sill portion of the window which would otherwise receive the water, a metal plate, this plate being virtually a bottom plate for the channel and protecting the wood of the window in the manner above noted.

The present invention involves a special form of bottom plate which may be made from metal or any other suitable material, the same being constructed in a peculiar way to coact with the fastening screws or members that secure the channel to the window sill so that the bottom plate will be pushed into its proper position relative to the bottom portion of the channel incident to the attachment of the channel to the sill by the said screws or fastening means. And where the channel is of the type which is frequently used today, namely that construction which is intended to be seated in the angle formed between the stool of the window frame and the main sill thereof, the bottom plate construction which cooperates with the screw or other fastening means is designed to have the additional function or effect, according to this invention, of tending to force such a channel member snugly into the angle between the stool and main window sill above referred to.

In carrying out the foregoing, according to my invention, I avail of a peculiar resilient V-shaped flange at the inner edge of the bottom plate, said flange adapted to cooperate with a depending flange on the bottom portion of the channel member and with the screw or other fastening means to accomplish the objects above noted.

Additionally, the said flange is peculiarly formed so as to provide a lower biting edge capable of digging into the wood of the main sill, or other base portion of the window frame on

which it may be mounted as an incident to the firm fastening down of the channel member on said sill, an air tight and water tight connection being obtained between the bottom plate and sill in this manner, having the especial advantage of eliminating the necessity of using a calking material or substance between the bottom of the channel and the top of the base or sill portion of the window on which it is mounted.

With the foregoing and other objects in view, certain adaptations of my invention are illustrated in the accompanying drawing, but it is to be understood that I do not wish to be limited to the exact constructions depicted therein as the latter may be modified in certain respects within the purview of my invention, and the scope of the appended claims.

In said accompanying drawing:—

Figure 1 is a sectional view of the lower edge portion of an in-swinging casement sash of a French window showing weatherstrip equipment including that of the present invention, the bottom plate construction comprising the novel feature of the invention being associated with a channel member located at the angle between the stool of the window frame and the main base sill.

Figure 2 is a view similar to Figure 1 showing a different construction of window frame and sill; also, the application of the invention to a slightly different construction of channel member.

Figure 3 is a perspective view of the bottom plate showing the resilient V-flange formation more clearly.

Figure 4 is a fragmentary view somewhat similar to Figure 2, but less full in illustration, depicting a modified adaptation of the invention, wherein the resilient flange is up-turned instead of down-turned, as is true in respect to the construction of Figures 1 to 3 inclusive.

Figure 5 is a view similar to Figure 3, but showing the modified form of the bottom or metal plate employed beneath the channel according to the construction of Figure 4.

In Figure 1 the base or main sill of the window frame is designated A. The stool at the inner edge of the sill A is designated B, and the swinging sash of the French window is denoted C. Beneath the lower edge of the sash C is located the channel 1 consisting of a base having the inner vertical flange 2, and the outer vertical flange 3. A hook weatherstrip member 4 cooperates with the lip 5 of the flange 3 and a rain drip member 6 connects with the portion 7 of the hook weatherstrip member 4.

The weatherstrip equipment comprising the parts 4, 5, 6, and 7, does not form a part of the invention of this application.

The base or bottoms of the channel 1 is formed with flanges 8, 9 and 10, vertically disposed and spacing the bottom of the channel from the sill A. Near the outer ends of the bottom of the channel 1 are the weep holes 11, which communicate with the outer sub-channel 12 of the channel member 1 and the flange 8 is formed with lateral weep holes shown in dotted lines at 13, through which water trapped in the channel will pass to the outer side of the window and weatherstrip construction.

The bottom or zinc plate beneath the channel member 1, as has been previously referred to herein, is designated 14, and really forms the bottom of the outer sub-channel 12, though it extends partly at its inner edge into the inner sub-channel 15, beneath the channel member 1. This bottom plate 14 is seen best in Figure 3, as being equipped at its inner edge with an upwardly and downwardly resilient member or flange 16 of somewhat V-shape in cross section, the sides of said flange or resilient V-member being compressible toward each other. The outer side of the member 16 engages with the inner side of the flange 9, depending from the bottom of the channel member 1 and the inner side of said member 16 is adapted to be engaged and pressed against by the screw or similar fastening 17 used for attaching the channel member 1 to the sill A.

The action of the parts 17 and 16 and 14 will be quite apparent upon brief reference thereto. The operation of screwing home the screw 17, attaching the channel member 1 in place on the sill A, tends to push against the inner side of the resilient V-member 16 and by doing this tends to force the V-member outwardly from the stool B to cause its outer side to snugly hug or fit against the inner side of the flange 9 of the member 1. It is notable that the right hand or inner side of the V-member 16 extends downwardly and has its edge terminating in a plane slightly below the plane of the plate 14.

45 The pressure of the flange 9 downwardly on the plate 14, as the screw 17 is screwed home in attaching the channel member 1 in place, causes the lower biting edge 16a of the member 16 to bite or sink into the wood of the sill A, thus establishing an air tight connection between the parts 14 and A, and doing away with the need for placing a calking compound in the inner sub-channel 15. The action of the screw 17 against the member 16 as the parts are placed and secured in proper position on the sill, will always tend to shift the plate 14 to its proper position illustrated in Figure 1, beneath the channel member 1.

Now when the channel member 1 is of the type used in the manner illustrated in Figure 1, not 60 only does the screw 17 act on the parts 16 and plate 14 in the manner stated, but the V-fold of the member 16, as the screw 17 is screwed home, tends to push the screw against the inner side of the opening in the bottom of the channel member 1 through which the screw passes. Naturally this pushing action tends to force the channel 65 1 snugly into the corner provided by the angle between the sill A and the stool B. The member 16, under the above conditions, will now be seen to act with a double function, namely, exercising a pushing effect outwardly upon the plate 14, and an inward pushing effect upon the channel member 1, in conjunction with the coaction of the screw 17.

75 In Figure 2, the construction of the invention

is like that previously described, excepting that the channel member 1 used, is of a slightly different form than the one illustrated in Figure 1 and is employed upon a sill structure for the window which does not utilize the form of stool B shown in Figure 1.

There is illustrated in Figures 4 and 5, a modified form of the invention, in which I use a bottom zinc or plate 18 for the channel member which is formed with an up-turned V-flange 19 instead of the down-turned type of flange shown in Figures 1 to 3 inclusive. The flange 19 has the resilient function of the flange 16 so as to accomplish the same results in so far as tending to force the plate 18 outwardly and the channel member 1 inwardly in the action of driving home the screw or fastening 17. Of course, the equivalent of the biting edge 16a is not provided in the construction of the bottom plate 18, with its V-flange 19.

From the foregoing it will be apparent that I 20 have devised a special bottom zinc or plate for my channel member type of weatherstripping of quite simplified construction but ensuring a proper positioning of the bottom plate in the assembly and attachment of the same and the channel 25 member to the sill.

Having thus described my invention, what I claim as new and desire to secure by Letters Patent of the United States, is:—

1. In weatherstrip means of the class described, 30 in combination, a sash, a sill, a channel member mounted on the sill below the sash, a bottom plate between the channel member and the sill, and a fastening member passing through the bottom of the channel member and into the sill to connect 35 these parts, the bottom plate being provided with means at its inner edge coacting with the fastening member and tending to push outwardly on the bottom plate to properly position it in respect to the channel member.

2. In weatherstrip means of the class described, 40 in combination, a sash, a sill, a channel member mounted on the sill below the sash, a bottom plate between the channel member and the sill, and a fastening member passing through the bottom of the channel member and into the sill to connect 45 these parts, the bottom plate being provided with means at its inner edge coacting with the fastening member and tending to push outwardly on the bottom plate to properly position it in respect to the channel member, and 50 additionally formed so as to coact with the fastening means to tend to cause the same to press the channel member in one direction for the purpose set forth.

3. In weatherstrip means of the class described, 55 in combination, a sash, a sill, a channel member mounted on the sill below the sash, a bottom plate between the channel member and the sill, and a fastening member passing through the bottom of the channel member and into the sill to connect 60 these parts, the bottom plate being formed at its inner edge with a resilient flange to cooperate with said fastening member to force the bottom plate outwardly into proper position beneath the 65 channel.

4. In weatherstrip means of the class described, 70 in combination, a sash, a sill, a channel member mounted on the sill below the sash, a bottom plate between the channel member and the sill, and a fastening member passing through the bottom of the channel member and into the sill to connect 75 these parts, said bottom plate being formed at its inner edge with a downwardly projecting flange adapted to bite into the sill, and the channel mem-

ber being provided with a downwardly extending flange on its bottom to press against the bottom plate to force said biting edge into the sill.

5. In weatherstrip means of the class described, in combination, a sash, a sill, a channel member mounted on the sill below the sash, a bottom plate between the channel member and the sill, and a fastening member passing through the bottom of the channel member and into the sill to connect these parts, said bottom plate having at its inner edge a V-shaped resilient flange to coact with the fastening member to properly position the bottom plate beneath the channel member as the fastening member is driven home.
10. 6. In weatherstrip means of the class described, in combination, a sash, a sill, a channel member beneath the sash and on the sill and formed with a flange extending downwardly from the bottom thereof, a fastening passing through the bottom of the channel member into the sill and the bottom plate beneath the channel member and said flange thereof and provided with a resilient flange at its inner edge intermediate the flange of the channel member and the said fastening member
15. 7. In weatherstrip means of the class described, in combination, a sash, a sill, a channel member beneath the sash and on the sill and formed with a flange extending downwardly from the bottom thereof, a fastening passing through the bottom of the channel member into the sill and the bottom plate beneath the channel member and said flange thereof and provided with a resilient flange at its inner edge intermediate the flange of the channel member and the said fastening member
20. 8. In weatherstrip means of the class described, in combination, a sash, a sill, a channel member beneath the sash and on the sill and formed with a flange extending downwardly from the bottom thereof, a fastening passing through the bottom of the channel member into the sill and the bottom plate beneath the channel member and said flange thereof and provided with a resilient flange at its inner edge intermediate the flange of the channel member and the said fastening member

which flange is compressed between the flange of the channel member and the fastening member when the latter is driven home into the sill.

7. In weatherstrip means of the class described, in combination, a sash, a sill, a channel member beneath the sash and on the sill and formed with a flange extending downwardly from the bottom thereof, a fastening passing through the bottom of the channel member into the sill and the bottom plate beneath the channel member and said flange thereof and provided with a resilient flange at its inner edge intermediate the flange of the channel member and the said fastening member which flange is compressed between the flange of the channel member and the fastening member when the latter is driven home into the sill, said resilient flange having a side extending downwardly below the plane of the bottom plate carrying same so as to bite into the sill incident to the pressure of the flange of the channel member bearing down on the upper surface of the bottom plate.
